UNITED STATES PATENT OFFICE

2,389,269

SURGICAL FIXTURE

William L. Mermis, Youngstown, Ohio

Application July 31, 1944, Serial No. 547,392

3 Claims. (Cl. 128—1)

This invention relates in general to surgical fixtures and, more particularly, a fixture or holding device adapted to position and hold the head, neck, and shoulders of a patient during a nasal or throat operation, such as a tonsillectomy, sinus surgery, or bronchoscopy.

The present invention has for its primary objects the provision of a device of the type stated which is simple and rugged in construction and can be quickly and accurately adjusted to the various desired positions in which the patient must be placed for the surgical procedures to be employed.

It is a further object of the present invention to provide a device of the type stated which will securely hold the patient in the desired position and will not accidentally shift during the course of the operation.

It is an additional object of the present invention to provide a device of the type stated which is compact and entirely portable so that it may be used with equal facility in the hospital operating room as an accessory to standard operating tables, in the physician's office or examining room, or carried into the private sick room by rural practitioners, for example.

And with the above and other objects in view, my invention resides in the novel features of form, construction, arrangement, and combination of parts presently described and pointed out in the claims.

In the accompanying drawing (one sheet)—

Figure 1 is a top plan view of a surgical fixture constructed in accordance with and embodying the present invention;

Figure 2 is a side elevational view of the surgical fixture; and

Figure 3 is a transverse sectional view taken along line 3—3 of Figure 2.

Referring now in more detail and by reference to the drawing which illustrates a preferred embodiment of the present invention, 1 designates a frame member, formed preferably of sheet metal, having sufficient thickness to provide the desired strength and structurally stiffened by a solid marginal bead 2, welded or otherwise rigidly secured upon the upper face thereof. The frame 1 is formed so as to provide an end portion *a* adapted to lie beneath the back of a patient and having a transverse width, more or less suitable for such purpose. Midway between its ends, the frame 1 curves outwardly and is widened to provide a shoulder portion *b*, then narrowing in the formation of a neck portion *c* and finally extending outwardly in the provision

of a head portion *d*. By reference to Figures 1 and 2 the particular confirmation of the frame member will be apparent. It will be noted that the frame 1 is bent upwardly in the region of the shoulder portion *b* so that the end portion *a* and the head portion *d* will lie more or less in the same plane and the neck portion *c* will extend sharply downwardly from the shoulder portion *b* to the head portion *d*. The frame 1 is furthermore provided in the region of the shoulder portion *b* and end portion *a* with a relatively large aperture 3 and swingably mounted for relatively free movement within this aperture 3, by means of hinges 4, is a back rest panel 5, likewise formed of sheet metal and marginally stiffened by a peripheral solid bead 6. The frame 1 and the back rest panel 5 thickly padded and upholstered upon their upper faces and lateral margins with a sanitary, sterile and water-proof covering, as best seen in Figure 3.

Rigidly mounted upon the under-face of the frame 1, in the region of the shoulder portion *b*, is a U-shaped cross frame 7, having vertical legs 8 and a flat horizontal cross member or bight 9. It should be noted in this connection that the legs 8 are arranged so as to be substantially vertical when the surgical fixture is in use and furthermore the under-face of the cross member or bight 9 is disposed in the same plane as the portions of the under-surface of the frame 1 which are in contact with the supporting table or bed, as best seen in Figure 2. The legs 8 are further provided with transversely aligned vertical slots 10 having, in their rearward vertical margins, a plurality of matching detent-notches 11.

Fixed upon and projecting downwardly from the under-face of the back-rest panel 5 are a pair of laterally spaced bifurcated lugs 12 and swingably mounted in the bifurcations thereof by means of hinged pins 13 are hanger rods 14 provided at their ends with a relatively strong horizontal latching bar 15 projecting at its opposite ends through the slots 10 and sized for releasable engagement within any one of the detent-notches 11. Secured at their ends to the latching bar 15 adjacent the hanger rods 14 are spiral springs 16 attached at their other ends to depending anchor lugs 17 secured upon and projecting outwardly from the under face of the frame 1 approximately at the point where the neck portion *c* joins the head portion *d*, for normally urging the bar in the direction of the head portion *d* and into engagement with the detent-notches 11, all as best seen in Figure 2. Swingably secured at its ends by means of rings 18 is an elastic band

19 having in its central portion a rather well padded transverse chin strap section 20.

In the use the surgical fixture may be placed upon an operation table or bed or any other suitable flat surface upon which a patient may assume a reclining position. The patient is thereupon placed upon the surgical fixture in such a manner, neck end portion *a* lies more or less under the small of the patient's back with the shoulder portion *b* more or less under the patient's shoulders and the head resting in a downwardly and backwardly bent position in the head portion *d*. It will be apparent that in this position the neck and head will be bent sharply backwardly so that the crown of the patient's head will actually be resting in the head portion *d* and the mouth of the patient will be so placed that the oral cavity is conveniently accessible for surgical operations. Furthermore, if desired the chin strap 20 can be looped over the patient's head and into engagement with the lower jaw or chin or as to hold the mouth in fully opened position for as long as surgeon or operator may desire.

Finally, because patients will vary in size and also because these kinds of operations require more or less backward tilting of the patient's neck and head, it is possible to adjust the back rest panel 5 upwardly or downwardly by manually shifting the latching bar 15 toward the end portion *a* against the tension of the springs 16 and swinging the back portion upwardly to the desired height, whereupon the latching bar 15 may be permitted to drop into the nearest detent-notches 11 and will hold the back rest panel 5 in such adjusted position. In actual practice the detent-notches can be formed, as shown in Figure 2 so that the back rest panel 5 may be merely pushed upwardly and the latching bar 15 will automatically shift in and out of successive detent-notches 11 as it moves upwardly, very in the manner of a ratchet. It will, of course, be understood that the latching bar 15 must be manually released in order to return the back rest panel 5 to initial position. It should also be noted that, when the surgical fixture is in actual use, the weight of the patient will be distributed along three transverse lines or areas and the shoulder load will be borne by the cross frame 7, as best seen in Figure 2.

It will be apparent that the surgical fixture of the present invention is relatively simple in construction and operation and is not only convenient for use as an accessory to operating tables and surgical beds in hospitals and offices but is also readily portable and may be transported by the physician or surgeon to the sick room of patients for the performance of minor surgical operations and examinations of the oral cavity or throat, in fact, surgical fixtures constructed in accordance with the present invention are extremely useful for the rural practitioners who frequently must perform a tonsillectomy or bronchoscopy in an area where hospitalization is not available.

It should be understood that changes and modifications in the form, construction, arrangement, and combination of the several parts of the surgical fixture may be made and substituted for those herein shown and described without departing from the nature and principle of my invention.

Having thus described my invention, what I claim and desire to secure by Letters Patent is:

1. A surgical fixture for use in supporting a human patient during the performance of surgical procedures and examinations, said fixture comprising a padded frame having a head-supporting section and an end section adapted to fit beneath the back and shoulder blades of the patient and being connected to the head-supporting section by an upwardly arched neck section, said end section being provided with a relatively enlarged aperture, a back-supporting member swingably mounted in the aperture for supporting the shoulders of the patient at different selected angular positions with respect to the head-supporting member, and manually releasable means for holding the back-supporting member in any one of its several positions of adjustment.

2. A surgical fixture for use in supporting a human patient during the performance of surgical procedures and examinations, said fixture comprising a padded frame having a head-supporting section and an end section adapted to fit beneath the back and shoulder blades of the patient and being connected to the head-supporting section by an upwardly arched neck section, said end section being provided with a relatively enlarged aperture, a back-supporting member swingably mounted in the aperture for supporting the shoulders of the patient at different selected angular positions with respect to the head-supporting member, a pair of legs rigidly mounted on and extending downwardly from the frame in the region of the portion adapted to underlie the shoulders of the patient and being provided with vertical slots having a series of vertically spaced detent notches, a transversely extending latching bar swingably mounted on and depending from the back-supporting member for engagement at its ends in the detent notches, and spring means for normally urging the latching bar into engagement with the detent notches.

3. A surgical fixture for use in supporting a human patient during the performance of surgical procedures and examinations, said fixture comprising a padded frame having a head-supporting section and an end section adapted to fit beneath the back and shoulder blades of the patient and being connected to the head-supporting section by an upwardly arched neck section, said end section being provided with a relatively enlarged aperture, a back-supporting member swingably mounted in the aperture for supporting the shoulders of the patient at different selected angular positions with respect to the head-supporting member, a pair of legs rigidly mounted on and extending downwardly from the frame in the region of the portion adapted to underlie the shoulders of the patient, said legs being connected at their lower ends by a transversely extending cross member the under face of which lies in the same plane as the portions of the frame underface upon which the fixture rests when in operative position, said legs further being provided with vertical slots having a series of vertically spaced detent notches, a transversely extending latching bar swingably mounted on and depending from the back-supporting member for engagement at its ends in the detent notches, and spring means for normally urging the latching bar into engagement with the detent notches.

WILLIAM L. MERMIS.
